UNITED STATES PATENT OFFICE.

GERVAIS BAILLIO, OF PHILADELPHIA, PENNSYLVANIA.

ELECTROLYTIC CELL.

1,385,655.

Specification of Letters Patent. Patented July 26, 1921.

Application filed October 25, 1920. Serial No. 419,223.

To all whom it may concern:

Be it known that I, GERVais BAILLIO, a citizen of the United States, residing at Philadelphia, county of Philadelphia, and

5 State of Pennsylvania, have invented a new and useful Improvement in Electrolytic Cells, of which the following is a full, clear, and exact description, reference being had to the accompanying drawings, which form 10 a part of this specification.

This invention relates to an improvement in electrolytic cells for the electrolysis of solutions, and is designed to provide an efficient cell which is cheap of construction, 15 and which can readily be assembled and taken apart.

The precise nature of my invention will be best understood by reference to the accompanying drawings, which will now be 20 described, it being premised, however, that various changes may be made in the details of construction, without departing from the spirit and scope of my invention as defined in the appended claims.

25 Figure 1 of the drawings is a side elevation, partially in section, of one form of cell constructed in accordance with my invention.

Fig. 2 is a sectional plan view thereof.

30 Fig. 3 is a plan view.

Fig. 4 is a vertical section to an enlarged scale.

Fig. 5 is a detail elevation, with parts broken away, of one of the side members, 35 several of the anodes, and portions of the top and bottom of the cell.

Fig. 6 is a perspective view of one of the anode supports.

A cell built in accordance with my invention, such as illustrated in the drawings, 40 comprises side members 2, a U-shaped member having a base 3 and flanges 4 at each end thereof, which forms the bottom and ends of the cell, and a top 5.

45 The above members are molded of concrete or other suitable plastic material and are secured to each other by means of screw clamps 6, there being a sheet 7 of asbestos between each side member and the other 50 members which form gaskets as well as filters and baffles between the cell chambers.

The bottom forming member 3 is provided with a plurality of parallel longitudinal V-shaped grooves for centering and retaining the anodes 8 in proper relation to the 55 cathodes 9. The anodes 8, which I preferably form of graphite, are each provided with a porcelain socket or base member 10 at the lower end, which socket members are provided with triangular shaped flanges on 60 their lower faces for engagement with grooves in the bottom, and upwardly extending triangular flanges on the upper faces and at the edges thereof, to form seats for the bodies of the anodes. 65

These anodes are also each provided with an upwardly extending stem or terminal 11, which extend through suitable orifices in the top 5.

The cathodes 9 are formed of perforated 70 sheet iron with outwardly extending flanges 12, which form anchoring means for retaining the cathodes in position on the sides, and are also provided with terminals 13, which extend through the sides 2. 75

14 and 15 are outlets from the chambers or recesses 16 formed in the inner faces of the sides 2 under the cathodes 9, 18 is an outlet through the top 5 from the anode compartment, and 17 is an inlet opening 80 through the top 5 for the admission of the liquid to be treated.

The various cell forming members are formed of concrete or other plastic material in suitable molds to form the cavities and 85 openings therein, and the cathodes are secured in position in the sides 2 during the molding, in such a manner that the outer faces thereof are flush with the inner faces of the side members. 90

The bodies of the anodes 8 are also formed in suitable forms in connection with the previously formed bases and stems to form unitary structures.

In assembling a cell the anodes are placed 95 in position on the bottom or web 3, and the top 5 is then placed in position on the seats on the ends or flange members 4. A sheet of asbestos is then placed on each side of the structure and the sides are then placed in 100 position and secured by the clamps 6. The edges of the sheets 7 of asbestos form pack-

ing between the abutting members, while the central portions form baffles and strainers between the cathodes and anodes.

The flanged porcelain base members form 5 protectors for the lower ends of the anodes as well as centering means for spacing the anodes with relation to the cathodes.

The cell can also be used as a tank cell by 10 merely making a luted joint between the side members and the body forming portion, and permanently securing the parts together.

If it is desired to form a cell of a different shape than that shown in the drawings, such as a circular cell, the sides and 15 bottom forming portions would be shaped accordingly, and secured to each other.

The advantages of my invention result from the provision of an electrolytic cell which can readily be taken apart for 20 cleaning and repairing and which can readily be reassembled again.

Further advantages result from the elimination of joints on the side of the cell by combining the cathode box, cathode sheet 25 and side of cell in a single side member, whereby brine leakage is avoided, and the chance of air leakage into the anode compartment with consequent dilution of the chlorin gas is reduced to a minimum, when 30 the cell is used for the electrolytic treatment of salt solution. The hydrogen gas from the cathode compartment can be readily collected without making any change in the manner of assembling the cell.

35 The cost of fabrication of the graphite anode is small as there are no threaded or doweled joints, or any joints in the anode below the surface of the brine.

Having now fully described my invention, 40 what I claim and desire to protect by Letters Patent is:—

1. An electrolytic cell comprising a body forming portion and abutting side members, a cathode in each side member, a sheet of 45 porous material interposed between the abutting faces of the body and each side member, means for clamping the side members against the body, and means for positioning an anode in the body portion between the cathodes.

50 2. An electrolytic cell comprising a body forming portion and abutting side members, a cathode in each side member, the outer faces of the cathodes being in the same plane as the inner faces of the side members, a 55 sheet of porous material interposed between the abutting faces of the body and each side member, means for clamping the side members against the body, and means for positioning an anode in the body portion between 60 the cathodes.

65 3. An electrolytic cell comprising a body forming portion and abutting side members, a cathode in each side member, a sheet of asbestos interposed between the abutting 65 faces of the body and each side member,

means for clamping the side members against the body, and means for positioning an anode in the body portion between the cathodes.

4. An electrolytic cell comprising a body forming portion and abutting side members, 70 a cathode in each side member, the outer faces of the cathodes being in the same plane as the inner faces of the side members, a sheet of asbestos interposed between the abutting faces of the body and each side 75 member, means for clamping the side members against the body, and means for positioning an anode in the body portion between the cathodes.

5. An electrolytic cell comprising a body forming portion and abutting side members, a perforated cathode in each side member, the outer faces of the cathodes being in the same plane as the inner faces of the side members, there being a recess in the inner 80 face of each side member under the cathode, a sheet of asbestos interposed between the abutting faces of the body and each side member, means for clamping the side members against the body, and means for positioning an anode in the body portion between the cathodes. 85

6. An electrolytic cell comprising a body forming portion and abutting side members, a cathode anchored in each side member, each 90 cathode having a terminal extending through its side member, a sheet of asbestos interposed between the abutting faces of the body and each side member, means for clamping the side members against the body, and means for positioning an anode in the body portion between the cathodes. 95

7. An electrolytic cell comprising a U-shaped body portion forming the ends and bottom of the cell, side members abutting 100 said body forming portion, there being a recess in the inner face of each side member, a perforated cathode covering each recess and anchored to its side member, the outer faces of the cathodes being flush with the 110 inner faces of the side members, a sheet of asbestos interposed between each side member and the body portion, a top supported on the ends between the sheets of asbestos, the width of the top being equal to the width 115 of the body portion, the top having spaced openings therethrough, anodes supported on the bottom, each anode having a terminal extending through an opening in the top, means on the bottom member and the anodes 120 for centering the anodes with relation to the cathodes, terminals on the cathodes extending through their respective side members, and means for clamping the sheets of asbestos between the body portion and top, and 125 the side members.

8. A concrete side member for an electrolytic cell having a cavity in one face thereof, and a perforated cathode anchored thereto and covering said cavity, the outer face of 130

the cathode being in the same plane as the face portion of the side member surrounding said cavity.

9. A concrete side member for an electrolytic cell having a cavity in one face thereof, a terminal for said cathode extending through the body thereof, and a perforated cathode anchored thereto and covering said

cavity, the outer face of the cathode being in the same plane as the face portion of the side member surrounding said cavity.

In testimony of which invention, I have hereunto set my hand, at Philadelphia, Pa., on this 21st day of October, 1920.

GERVAIS BAILLIO.
